Phineas Davis Baltimore C 162

Letters Patent July 29. 1834.

The Schedule referred to in these Letters Patent are making part of the same Containing a description in the words of the said Phineas Davis himself of his Improvement in the mode of Casting Cast iron Wheels for Rail-road Cars and Carriages.

Whereas it has been found that in the casting of what are called chilled wheels for rail-road Cars that the part of the wheel which is most liable to wear namely the side Cone or Curve between the track of the wheel and the flangeth, is usually less hard than the other parts for the obvious reason that the metal there is less rapidly cooled by the air. Now be it known that I Phineas Davis of the City of Baltimore in the State of Maryland have invented a new and improved mode of Casting such wheels in which by the cooling influence of a hoop or ring of wrought iron made and placed in the flask or mould at the time of casting in a way to be presently set forth I have succeeded in removing this difficulty and I do hereby declare that the following is a full and exact description thereof.

Those acquainted with the business of Casting iron are aware that the operation of Casting consists in placing within the mould, so as to make a part thereof a piece or pieces of iron which when the metal is fused is rapidly cooled. That portion of the wheel which it is in contact with the track in the casting of wheels for rail road Cars, the wheel consists of an iron hoop of considerable thickness and with which the whole face of the wheel including the flangeth and rim is in contact but from its form as it has already indicated there is one part of it which with the flangeth which is less rapidly cooled than the others. To remove this difficulty I employ what may be denominatet an internal shill: this consists of an iron hoop or ring which I usually form of round rods half an inch in diameter giving to the hoop a ring such a diameter as shall cause it when laid on the flask and the casting made to be surrounded

ly and completely enclosed within the cast metal base is stored about
half an inch within the body of that part of the wheel which forms the
circular cross from striking an opponent the centre thereof. But as in
normal thickness of the ring of such wheel the said ring would
remain on the inside by only a thin shell of metal of from such a thin
projection or thickness opposite thereof on the inside of the part of the
wheel as will cause the metal to cool it about three eighths of an inch
from boundary are well acquainted with the means of supporting such
parts as the more described ring will be found to have adopted of
making the following parts of which
may be 1/16 of an inch thick 1/4 of an inch broad and 4 inches long
and one end of each of these I found round the ring so as to clasp it tightly
the remainder of the strap forming a shank or bearing which rests upon
the said mother lower flask. These clasp shall be at equal distances apart
and when in the mould the said iron was the centre of the wheel. The
pattern must be so made that the parting of said iron in the flask will
be opposite the centre of the ring, during some of the usual description
should be used in making the mould. The ring before being placed in
the mould should be so surface, that it might by filing or otherwise
be most easily heated to the temperature of boiling, so as to
disperse any moisture or other corporal matter which might otherwise
have been in it. The casting should be performed immediately
after placing the ring in the flask. Although I have described the mode
of procedure in casting iron in other parts of the present for forming wheels
nothing which are intended a ring of wrought iron, I do not claim
them however as making any part of ring, invention but I do claim the
using a hoop or ring of wrought iron to form and cast within the
body of a iron, steel, in such manner as to operate as an internal
ring to contract rapidly and consequently to harden the part which shall
remain within the body of the iron to be henceforth no more.
